UNITED STATES PATENT OFFICE.

JOHN FRANK ETTER, OF CHAMBERSBURG, PENNSYLVANIA.

MOP WRINGER.

Application filed April 7, 1923. Serial No. 630,525.

To all whom it may concern:

Be it known that I, JOHN FRANK ETTER, a citizen of the United States, residing at Chambersburg, in the county of Franklin and State of Pennsylvania, have invented 5 certain new and useful Improvements in Mop Wringers, of which the following is a specification, reference being had to the accompanying drawings.

10 This invention relates to certain improvements in mop wringers and it is an object of the invention to provide a novel and improved plate of this general character which can be readily and conveniently positioned in place on the top of a bucket or the like to facilitate the squeezing or rinsing of a mop.

15 The invention consists in the details of construction and in the combination and arrangement of the several parts of my improved mop wringer whereby certain important advantages are attained and the device rendered simpler, less expensive and otherwise more convenient and advantageous for use, as will be hereinafter more fully set forth.

20 The novel features of my invention will hereinafter be definitely claimed.

25 In order that my invention may be the better understood, I will now proceed to describe the same with reference to the accompanying drawings, wherein:—

30 Figure 1 is a view in perspective illustrating a mop wringer constructed in accordance with an embodiment of my invention and in applied position, a mop for coaction therewith being indicated by broken lines;

35 Figure 2 is a sectional view taken through the mop wringer on the line 2—2 of Figure 1, looking in the direction of the arrow, a second position of the handle member being indicated by broken lines; and

40 Figure 3 is a transverse sectional view taken substantially on the line 3—3 of Figure 2, looking in the direction of the arrow.

45 As disclosed in the accompanying drawings, my improved mop wringer comprises 50 a frame F preferably formed of an elongated strand of requisite gauge and substantially rigid. The frame F is substantially in the form of a U with the side or parallel arms 1 thereof of a length to bridge the top of a bucket B or the like. The extremities of the arms 1 are continued by

the depending extensions or arms 2 while the intermediate or base portion 3 of the frame is downwardly offset. The extensions or arms 2 together with the particular arrangement of the intermediate or base portion 3 assures the device in its entirety being effectively maintained in applied position upon the bucket.

55 P denotes a plate having its side marginal portions returned as at 4 to provide sleeves or barrels 5 surrounding the side members 1 of the frame F and clinched or otherwise secured thereto whereby the plate P has a fixed position relative to the frame F, 70 said plate being of a length less than that of the arms 1.

60 As herein disclosed the end marginal portion of the plate P opposed to the base or intermediate portion 3 of the frame F is 75 substantially defined by a depending flange 6 while the opposite end marginal portion of the plate P is returned to provide a sleeve or barrel 7.

65 H denotes an elongated handle member 80 formed of a strand of requisite gauge and rigidity and having one end portion provided with a laterally extending arm 8, said arm 8 being continued by a reversely disposed arm 9 freely disposed through the sleeve or barrel 7 whereby the handle member H is pivotally engaged with the plate P. The free extremity of the arm 8 is provided with a laterally disposed extension or arm 10 90 which provides a stop which by contact from below with the plate P limits the swinging movement of the handle H when raised into working position. When the device is not in use the handle member H may 95 be readily swung downward to a position contacting with the plate P where the device when not in use will be compacted and occupy a minimum amount of space.

100 My improved mop wringer is particularly adapted for use in connection with a mop of the character disclosed in my Patent No. 1,444,166 dated February 6, 1923 although I do not wish to be understood as limiting myself in this respect.

105 The plate P is provided with a plurality of minute openings or perforations 11 so that when a mop is pressed upon the plate the liquid squeezed from the mop will be readily received within the bucket B.

110 From the foregoing description it is thought to be obvious that a mop wringer constructed in accordance with my inven-

tion is particularly well adapted for use by reason of the convenience and facility with which it may be assembled and operated, and it will also be obvious that my 5 invention is susceptible of some change and modification without departing from the principles and spirit thereof and for this reason I do not wish to be understood as limiting myself to the precise arrangement 10 and formation of the several parts herein shown in carrying out my invention in practice except as hereinafter claimed.

I claim:-

15 A mop wringer comprising a substantially U-shaped frame, the intermediate portion thereof being offset with respect to the side members, the free extremities of the side members being continued by arms disposed in the same general direction as the

offset of the intermediate portion of the frame, said side members of the frame being of a length to permit the same being supported upon a bucket, a plate secured to the side members and bridging the space therebetween, said plate being of a length 20 less than the side members, one end marginal portion of the plate having a tubular flange disposed therealong, an elongated handle having one end portion provided with a laterally extending arm disposed 25 through said flange, said arm having an angularly disposed extension for contact from below with the plate to limit the swinging movement of the handle when raised into working position. 30 35

In testimony whereof I hereunto affix my signature.

JOHN FRANK ETTER.
